Filed July 28, 1958, Ser. No. 751,524

3 Claims. (Cl. 110—8)

This invention relates to incinerators for burning garbage, trash and similar waste materials, and has for its principal object to provide an incinerator of this character with a compartment wherein the waste materials are burned and the smoke and gases which result are mixed with combustion supporting air and subsequently consumed in passage through a gas flame to an auxiliary gas burning chamber, and thereby eliminate the discharge of smoke and odors into the atmosphere.

Other objects of the invention are to provide an incinerator that is of simple construction, capable of withstanding high temperatures, and free from clogging.

It is also an object of the invention to provide for withdrawal of smoke from around the door of the trash burning compartment and effect passage thereof through the gas burning chamber, thereby eliminating any tendency for leakage of smoke around the door opening.

In accomplishing these and other objects of the invention, I have provided improved structure, the preferred form of which is illustrated in the accompanying drawings, wherein:

FIG. 1 is a vertical section through an incinerator embodying the features of the present invention, the section being taken on the line 1—1 of FIG. 2 and looking in the direction of the arrows.

FIG. 2 is a horizontal section on the line 2—2 of FIG. 1.

FIG. 3 is a vertical section taken at right angles to the section of FIG. 1 on the line 3—3 of FIG. 4.

FIG. 4 is a horizontal section on the line 4—4 of FIG. 1.

FIG. 5 is a perspective view of the shaker grate.

FIG. 6 is a perspective view of the afterburner funnel member and the secondary fuel burner prior to installation in the incinerator and shown in their relative positions.

Referring more in detail to the drawings:

1 designates an incinerator constructed in accordance with the present invention for burning garbage, trash and other combustible materials without discharge from the incinerator of smoke and odors ordinarily resulting from burning such materials. The incinerator includes an outer casing 2 having side walls 3—4, a front wall 5, and a rear wall 6, supported from the floor on a base 7. The casing 2 also includes a top 8 joining with the side, front and rear walls by a telescoping joint as indicated at 9, FIGS. 1 and 3. Supported transversely on the base 7 is a bottom 10 suitably connected with the front, rear and side walls by a flange 11. Extending transversely above the bottom 10 and terminating short of the rear wall 6 is a grate 12 that cooperates with a transverse partition 13 and the bottom 10 to provide an ash compartment 14 therebetween. The ash compartment has an opening 15 through the front wall 5. The partition 13 extends vertically between the bottom 10 and the rear edge of the grate 12 in inwardly spaced relation from the rear wall 6 to provide a burner compartment 16 that is closed at the bottom by a horizontally extending plate 17 and at the top by a plate 18 having an opening 19 therethrough, as best shown in FIG. 1. The opening 19 extends substantially the width of the grate and passes flame from a burner 20 into a gas and smoke burning chamber 21, as later to be described.

2

The smoke burning chamber 21 is separated from the trash burning compartment by a main vertical partition 22 that preferably comprises a cast metal plate having an inturned flange 23 at its lower end for supporting the rear of the grate. Formed in the partition 22 directly above the flange is an opening 24 extending transversely of the partition and which has its lower edge provided with an upwardly sloping flange 25 extending outwardly over the burner 20 to direct smoke and gas into the flame from the burner and prevent any fly ash from dropping onto the orifices of the burner. The upper edge of the opening is provided with a horizontal flange 26 that provides a ledge for seating one side of an after-burner funnel 27, to be hereinafter described.

15 The grate 12 includes a marginal portion 28 surrounding a downwardly sloping bowl-like portion 29 having a rectangular opening 30 in the bottom thereof. Mounted in the opening 30 is a shaker plate or grid 31. The marginal portion at the innermost side of the grate slopes 20 downwardly, as at 32, to seat on the inturned flange 23 of the main partition 22. The bowl portion 29 of the grate has apertures 34 in the sides thereof to provide for passage of combustion supporting air from the ash compartment into an upper trash burning compartment 35, 25 which is provided in the housing on the front side of the partition 22. The shaker plate 31 is best shown in FIG. 5, and has an arm 36 extending forwardly toward the open end of the ash compartment for shaking the ashes into the ash compartment. The ashes are caught in an ash pan 37 that is slidable into the ash compartment and which has a front wall 38 of a size and contour to provide a door 39 for closing the open end of the ash compartment. The door portion 39 is provided with an opening 40 in registry with the shaker arm. The door also 35 includes a handle 41 by which the pan may be moved into and out of the ash compartment.

The burner 20 includes a longitudinal section 42 which extends the length of the burner compartment and a section 43 that is positioned in the ash compartment below 40 the downwardly inclined marginal portion of the grate, as best shown in FIG. 1. Both sections of the burner are preferably supplied with a fuel mixture through a manifold 44. The manifold is connected with a fuel supply and controls therefor, which for simplicity of illustration are indicated by a simple valve 44', but it is understood that automatic safety controls may be provided, as in other modern gas burning appliances.

In order to protect the walls of the casing in the heat 50 zone of the trash burning compartment, they are preferably lined with refractory tile, as indicated at 45, the tile extending from the partition 22, along the sides and front wall of the casing, as best shown in FIG. 2. The remaining portion of the side walls and the rear wall are protected by a lining 46, spaced inwardly from the casing to accommodate an insulating material 47 therebetween, which may consist of rock wool or similar heat resistant material.

The top of the incinerator has a door opening 48 directly over the trash burning compartment, through which the trash and other material to be burned is inserted into the incinerator. The opening 48 is closed by a door 49 that is suitably hinged at one side to the top. The door 49 includes an inner portion 50 that is spaced from the outer portion 51.

The innermost corners of the grate 12 are provided with openings 52 and 53 and extending upwardly therefrom are ducts or flues 54 and 55, by which air from the ash compartment is conducted around the trash and discharged into the upper portion of the trash burning compartment for mixture with smoke and gases evolved from the trash when the incinerator is in operation. Extending

between the ducts and having its lower edge seated in a groove 58 (FIG. 1) of the inclined portion 32 of the grate 12 is a secondary partition 57 that extends upwardly from the grate and terminates as the top of the ducts 54 and 55 to cooperate with the partition 22 in providing a down flue or duct 58 that connects with the opening 24 in the lower portion of the main partition. The upper or inlet end of the duct 58 is covered by a screen 59 which permits passage of the smoke, air, and gas for mixture in the downflow duct but which excludes solid particles of the trash from being drawn out of the trash compartment.

The after-burner funnel 27 is best shown in FIG. 6, and includes downwardly and outwardly flaring sides 60-61 and ends 62-63 to provide a base portion 64 of sufficient size to close off the lower portion of the smoke combustion chamber and to seat upon the inturned flange 23 of the main partition and a flange 65 that is fixed to a partition 66 in the rear of the smoke burning chamber. The inclined sides of the member 27 funnel the mixture through an elongated outlet opening 67 defined by vertical extensions 68 of the sides and ends of the inclined portions 60-61 and 62-63 and thus provide means through which the air, gas and smoke mixture is directed into the smoke combustion chamber. The partition 66 is spaced from the inner face of the rear wall 6 of the casing and joins with the horizontal portion 18 to constitute a dead-air space 69 to supplement the insulation afforded by the rock wool. The partition 66 terminates short of the top of the casing to leave room in the rear wall for a check draft device 70.

The check draft 70 comprises a collar 71 that extends laterally through the wall of the casing, and the outer end 72 thereof is normally closed by a swing damper 73 that is responsive to updraft to control the draft on the burners, the damper 73 being of a type to close under downdraft through the flue connection.

There may be a tendency for the smoke accumulating in the top of the trash burning compartment to escape through the door 49, and to avoid this difficulty, a secondary down flue or flow duct 74 is provided. The downflow duct 74 is provided by a partition 75 that is spaced from the main partition 22 and which depends from the top 8 downwardly to terminate at a level above the outlet 67 of the after-burner funnel 27, thereby bypassing the main downflow duct 58 and after-burner funnel 27, so that a more direct draft is provided to a flue outlet connection 76 that is located in the top 8 in line with the smoke burning chamber 21 for removing the smoke that tends to escape through the door, particularly if the door has not properly seated.

When installed, the incinerator, constructed and assembled as described, may be placed in any location which is convenient for connection with a chimney or flue. A gas supply is connected with the manifold 44 of the burner 20 and the incinerator is ready for operation. The trash, garbage or other waste to be consumed is inserted through the door opening 48 to pile up upon the grate 12, but leaving space above the outlet of the air ducts 54 and 55 for movement of the smoke and gases evolved from the burning material. Upon completion of the charge, the door 49 is closed and the burner is started so that the jets of the section 43 discharge flame through the openings 34 of the grate to dry out and ignite the material thereon and to maintain combustion responsive to flow of combustion supporting air that is drawn through the door opening 40 and from the ash compartment 14 due to draft through the flue connection 76. The smoke and gas evolved from the burning material rises responsive to the draft and passes through the screen 59 and downwardly through the flue 58 for discharge through the outlet 24 below the after-burner funnel 27. Simultaneously with operation of the burner section 43, the jets of the section 42 discharge a flame across the outlet 24 and through the outlet opening 67 of

the funnel member, so that the gas and smoke discharged through the outlet must pass into direct contact with and through the flame for ignition and burning in the chamber 21, thereby resulting in an effective consumption of the odors and smoke, so that a smokeless gas is discharged through the flue connection 76.

In order to promote combustion of the burning gases and smoke in the smoke burning chamber, the draft also produces a flow of air through the ducts 54 and 55 which is drawn with the smoke and gases through the screen 59 for mixture in the downflow duct, thereby preparing the smoke and gases for substantially complete combustion after passing through the after-burner funnel 27.

If the draft through the flue connection should be greater than that to be maintained by the check draft device 70, the damper 71 will swing open to allow a sufficient amount of external air to enter the flue to reduce the draft through the burning compartments of the incinerator. In case of downdraft, the damper 73 will automatically close, to prevent any discharge through the check draft device.

After the trash burns down, additional trash may be inserted upon opening of the door 49.

Smoke might tend to escape around the door 49, but this is prevented by draft effected through the downflue 74 which carries the smoke directly into the lower portion of the gas burning chamber.

The ashes resulting from burning of the trash in the trash burning compartment drop through the opening 34 into the ash pan 37, or the ashes may be manually discharged from the trash burning compartment into the ash pan upon actuation of the shaker grate 31, to clear the trash burning compartment 35 for an additional charge of material to be consumed.

From the foregoing, it is obvious that I have provided an incinerator whereby waste materials are burned and the smoke and gases which result from the burning materials are subsequently mixed with combustion supporting air, ignited in passage through the gas flame, and burned in the smoke burning chamber, thereby eliminating discharge of smoke and odors through the flue connection.

It is also obvious that means are provided for eliminating escape of smoke around the door 49 by maintaining a direct draft from the vicinity of the door into the smoke burning chamber.

What I claim and desire to secure by Letters Patent is:

1. An incinerator including a casing having a trash burning compartment and a smoke burning chamber, a vertical partition means separating said compartment and said chamber and terminating short of the bottom of the casing, a grate extending transversely of the trash burning compartment at the terminal of the partition means and forming with the walls of the casing an ash compartment in the lower portion of the casing, said partition means having an opening near the grate to communicate the smoke burning chamber with the trash burning compartment, a door covering a trash insert opening in the top of the casing over the trash burning compartment and said door having an inner portion providing a supplemental closure for said opening, a burner below the grate for directing flame through the grate into the trash burning compartment for burning trash therein, a second partition means extending upwardly from the grate and spaced from the first partition on the trash burning side of said first partition and terminating within the upper portion of the trash burning compartment for providing a downflue connecting the upper portion of the trash burning compartment with said opening to the smoke burning chamber for conducting products of combustion resulting from burning of the trash into the smoke burning chamber, a burner located under the smoke burning chamber and below the opening for locating the flame therefrom across said opening.

in the direct path of the products of combustion issuing through said opening, an afterburner funnel immediately above the opening and having upwardly converging opposite sides extending from said sides of the smoke burning chamber to provide a constricted outlet to assure passage of the products of combustion into contact with said flame from the last named burner and into the portion of the smoke burning chamber above said afterburner to complete consumption of the products of combustion, a vent flue connected with the casing at the upper portion of the smoke burning chamber, and a partition depending from the top of the casing cooperating with the smoke burning side of the first partition means and terminating above the afterburner funnel to provide a downdraft duct bypassing the afterburner funnel, said downdraft duct having an inlet in communication with said trash insert opening for drawing smoke leaking past the supplemental closure into the burning products of combustion issuing from the afterburner funnel.

2. An incinerator as described in claim 1 and including an air duct extending upwardly from said grate and having an outlet terminating adjacent the top of the second partition for supplying combustion-supporting air to the products of combustion as they pass into said downflue.

3. An incinerator including a casing having a trash burning compartment and a smoke burning chamber, vertical partition means separating said trash burning compartment and said smoke burning chamber and terminating short of the bottom of the casing, a grate extending transversely of the trash burning compartment at the terminal of the partition means and forming with walls of the casing an ash compartment in the lower portion of the casing, said partition means having an opening near the grate to connect the smoke burning chamber with the trash burning compartment, a door covering a trash insert opening in the top of the casing over the trash burning compartment and said door having an inner portion providing a supplemental closure for said opening, a burner below the grate for directing flame through the grate into the trash burning compartment for burning trash therein, a second partition means

extending upwardly from the grate and spaced from the first partition means on the trash burning side of said first partition and terminating within the upper portion of the trash burning compartment for providing a downflue connecting the upper portion of the trash burning compartment with said opening to the smoke burning chamber for conducting products of combustion resulting from burning of the trash into the smoke burning chamber, a burner located under the smoke burning chamber and below the opening for locating the flame therefrom across said opening and into the direct path of the products of combustion issuing through said opening, flame and smoke directing means immediately above the opening into the smoke burning chamber and having sides providing a constricted outlet to assure passage of the products of combustion into contact with said flame from the last named burner and into the portion of the smoke burning chamber above said flame and smoke directing means to complete consumption of the products of combustion, a vent flue connected with the casing at the upper portion of the smoke burning chamber, and a partition depending from the top of the casing cooperating with the smoke burning side of the first partition means and terminating substantially at the flame and smoke directing means to provide a downdraft duct having an inlet in communication with said trash insert opening for drawing smoke leaking past the supplemental closure into the burning products of combustion within the smoke burning chamber.
